UNITED STATES PATENT OFFICE.

MILLS W. BARSE, OF OLEAN, NEW YORK.

STEAM-BOILER.

SPECIFICATION forming part of Letters Patent No. 319,545, dated June 9, 1885.

Application filed November 8, 1884. (No model.)

To all whom it may concern:

Be it known that I, MILLS W. BARSE, a citizen of the United States, residing at Olean, in the county of Cattaraugus and State of New York, have invented certain new and useful Improvement in Steam-Boilers, of which the following is a specification, reference being had therein to the accompanying drawings.

My invention relates to steam-generators wherein water-tubes are arranged to project across the fire-box and fire space or spaces and communicate with the water reservoir or chamber, and provide an extended heating-surface in direct contact with the flame and heated products of combustion in the fire-chamber.

The object of my invention is to compactly arrange said tubes in such manner as to expose them effectively to the action of the heat, and to adapt them to be readily accessible for cleansing and for repairs, and, furthermore, to arrange them with each other and with the water-chambers of the boiler in such a manner that a perfect circulation may be obtained of the water within the boiler, and the more rapid generation of steam thereby effected.

In the accompanying drawings, Figure 1 is a vertical longitudinal section of a stationary boiler set in brick-work with my improvements applied thereto; Fig. 2, a transverse vertical section on the line $\alpha\alpha$ of Fig. 1; Fig. 3, a perspective view of a crown-sheet and water-leg steam-generator, partly showing the interior of the fire-box and the ends of the water-tubes arranged therein. Fig. 4 is an enlarged sectional view of my improved elbow-box, to which the ends of the water-tubes are connected; and Fig. 5, an enlarged view in detail, showing the ends of a cluster of water-tubes arranged to illustrate a modification of my invention, as will hereinafter more fully appear.

A cylindrical water-drum, A, is set horizontally in brick-work B, to provide an inclosed space below the drum for the fire-box C at the forward end of the drum, and a fire-chamber, D, at the rear end thereof. The fire-box and fire-chamber are separated by a hollow fire-bridge, E, preferably formed of boiler-iron, and communication with the interior of the drum A by a neck or short con-

duit-pipe, F, which serves the additional purpose of a support for the middle portion of the water-drum. The fire-bridge is preferably of rectangular shape to form a solid wall extending from one side wall to the other side wall of the brick-work. A series of burners, G, secured to supply-pipes G', are in this instance arranged at the base of the fire-box, and the flame and products of combustion pass through the fire-box and over the fire-bridge into the fire-chamber in the rear end of the generator, from whence they escape through the flue H at the bottom and rear end thereof into the chimney or stack. Man-holes B' B'', arranged, respectively, in the front and rear end of the brick-work, are closed by doors M M, which admit of access to the interior of the fire-box and fire-chamber for repairs and for the removal of dust and other deposits.

The water-tubes I are made of two sections of wrought-iron or steel tubing, I' I'', of unequal lengths, arranged at a slight angle one with the other, and joined at their meeting ends by an elbow-box, J, of peculiar construction, as will hereinafter appear. The diverging ends of the tubes I' I'' pass through and into the front plate of the fire-bridge and project horizontally across the fire-box. The longer tube I' is arranged to enter the fire-box below the shorter tube I'', and extend across the interior of the bridge E and beyond the central line thereof, and the shorter tube I'' terminates inside the front plate and upon the forward side of the fire-bridge box, by which means the water in the fire-bridge, when heated, will pass out of the upper and short tubes upon one side of the bridge, and pass into the long tubes communicating with the other side of the fire-bridge, thus establishing a uniform circulation within said fire-bridge water-chamber, and causing the water from the elevated drum to first pass down upon the rear side of said fire-bridge into the tubes, and after having been heated pass up the forward side of said bridge back into the forward end of the drum. As an additional means for securing a circulation within the boiler, as above described, a diaphragm-plate, K, is arranged within and diametrically across the neck or conduit-pipe F, by which means the water will flow from the rear end of the

supply-drum A into the fire-bridge upon one side of the diaphragm, and back upon the other side of the diaphragm to the forward end of the drum.

- 5 The tubes in the fire-chamber at the rear of the fire-bridge are formed of short tubes L' L², joined together, and similar to the tubes I, but are connected with the interior of the fire-bridge in an inverse manner from that of the tubes I. The shorter tubes L' are arranged below the longer tubes L², and terminate upon the inner side of and close to the rear wall of the fire-bridge, and the longer tubes extend across the interior of the fire-bridge to the forward end thereof, by which means the colder water first enters the lower tubes from the cold-water side of the fire-bridge, and after being heated is discharged upon the hot-water side of said bridge to mingle with the hot water from the tubes I', and provide further means for preserving a uniform circulation with the boiler, such as previously described herein. The steam-dome N of the boiler is secured to the upper side of the water-drum 25 A, and is preferably arranged at the forward end thereof, by which means the hot water returning from the forward end of the fire-bridge box is conducted directly beneath the steam-dome. The elbow-box J, which joins the meeting ends of the water-tubes, is made rectangular, and of sufficient size to form a chamber into which the mud, sediment, and other matter carried through the tubes by this circulation of the water will be deposited. A hand-hole, 30 J', and cap-plate J² are arranged upon the side of the box opposite the ends of the water-tubes, and in line with the interior thereof, to admit of the insertion of a scraper or other tools for cleaning the tubes of scales or other deposit. 35 The door J² is arranged upon the inner side of the box, and is held in place by a bolt, J³, which passes through the door and through a crab-collar, J⁴, arranged to bear upon the outside of the box. 40 Grate-bars may be substituted in any well-known manner for the gas-jets shown in Fig. 1, and other modifications may be made without departing from the spirit of my invention—such, for instance, as the arrangement of tubes 45 shown in Fig. 5, wherein said tubes are in series arranged one above the other in still more inclined or diagonal lines, to connect with the water-bridge chamber of the boiler at their lower ends in the same vertical plane, and to 50 connect with said chamber at their upper ends in a different plane, by which means the cold water will descend in a plane parallel with the ascending plane of the hot water, thus forming a series of circulation-currents nearly similar to that described in connection with the arrangement of tubes illustrated in the main figures of the drawings, and previously described herein.

I do not limit myself to the arrangement of tubes applied to the forms of boilers herein shown, as they may be used upon other boilers with good effect, and, when desired, the

water-tubes may be connected to the water-legs of said boilers and arranged to project transversely across the fire-box and grate-bars. 70

The arrangement of the man-hole and doors in the front and rear end of the brick-work admits of convenient access to the interior of the fire-box and fire-chambers and to elbow-boxes at ends of the water-tubes, for cleaning 75 and repairing.

I claim as my invention and desire to secure by Letters Patent—

1. In a steam-generator, the combination, with a water-drum, of the hollow fire-bridge 80 connected to the under side of said drum and the pairs of water-tubes projecting across the fire-box, one of the tubes of each pair communicating with the rear portion of the interior of the fire-bridge, and the other with the front 85 thereof, substantially as and for the purpose described.

2. In a steam-generator, the combination, with the water-drum, of the hollow fire-bridge connected to the under side of said drum, the 90 water-tubes straight from one end to the other, but diverging from their elbow-box, and communicating with the interior of the fire-bridge, as set forth, and arranged to project across the fire-box, substantially as de- 95

3. In a steam-generator, the combination, with the brick-work of the furnace, of the water-drum, the hollow fire-bridge arranged to communicate with the under side of said drum, 100 the water-tubes projecting from the fire-bridge into the fire-chamber, and entering at acute angles their removable elbow-caps, and the covered man-holes formed in the brick-work of the furnace opposite said elbow-caps, sub- 105 substantially as and for the purpose described.

4. In a steam-generator, the water-tubes of unequal lengths, arranged in pairs at an angle one with the other, in combination with the elbow-box J, formed with the hand-hole J', arranged in line with the interior of both of 110 said tubes, the internally-arranged cap-plate J², and externally-arranged crab-collar J⁴, and the bolt J³, substantially as and for the purpose described. 115

5. The combination, with the water-leg, hollow fire-bridge, or water-reservoir of a steam-generator, of the water-tubes of unequal length, arranged one above the other, to project from said water-reservoir into the fire-space and re-enter said reservoir at their upper ends in a plane parallel with and outside of the vertical plane in which their lowermost ends terminate, substantially as and for the purpose described. 120

6. The combination, with the water-leg, hollow fire-bridge, or water-reservoir of a steam-generator, of the water-tubes formed of sections of unequal lengths, arranged one above the other, to project from one side of 130 said reservoir, substantially as and for the purpose described.

7. The combination, with the hollow fire-bridge, of a steam-generator formed of straight

tubes of unequal length, arranged in series upon opposite sides of said fire-bridge, to project into the fire-spaces in front and in rear thereof, and communicate with the interior of the fire-bridge and terminate therein upon opposite sides thereof, substantially as described.

8. The combination, in a steam-generator, of the water-drum, the hollow fire-bridge communicating therewith, the water-tubes projecting from said fire-bridge into the fire-chamber, and terminating upon opposite sides

of said fire-bridge, and a diaphragm-plate, *k*, arranged across the neck or conduit connecting the fire-bridge and water-drum, substantially as and for the purpose described.

In testimony whereof I affix my signature in presence of two witnesses.

MILLS W. BARSE.
